UNITED STATES PATENT OFFICE.

HARRY W. JONES, OF NEW YORK, N. Y., ASSIGNOR TO AMERICAN CAN COMPANY, OF NEW YORK, N. Y., A CORPORATION OF NEW JERSEY.

PAPER CAN OR RECEPTACLE.

1,130,825.

Specification of Letters Patent.

Patented Mar. 9, 1915.

Application filed January 30, 1911. Serial No. 605,456.

To all whom it may concern:

Be it known that I, HARRY W. JONES, a citizen of the United States, residing in New York, in the county of New York and 5 State of New York, have invented new and useful Improvements in Paper Cans or Receptacles, of which the following is a specification.

My invention relates to improvements in 10 paper or fibrous material cans or receptacles.

The object of my invention is to provide a paper or other fibrous material can or receptacle with a spout or pouring means, which will be of a simple construction, capable of being very cheaply manufactured, and which at the same time will be efficient 15 in operation and not interfere with the tight closure of the can.

My invention consists in the means employed to practically accomplish this object or result, the same consisting essentially in providing a wall of the paper or fibrous material can or receptacle, preferably the flat or top wall of its cover, with an opening and 20 closing sheet metal pouring spout having a back portion and two side wings, preferably quadrant shaped, one end of the spout being secured by an integral tang to the cover or other wall of the receptacle, and 25 the portion of the receptacle against which the back wall of the spout fits being preferably not cut out but secured at its margins so that the same may be readily ruptured in the act of opening or swinging outward 30 the hinged spout, which normally fits on the inside of the receptacle. The sheet metal opening and closing spout is further preferably provided with one or more tangs for securing it to the opening portion of the receptacle wall so that this opening portion 35 of the receptacle wall bounded by the scores may remain permanently attached to the spout. The tang or lip at the free or non hinged end of the spout serves as a finger 40 piece for engagement with the thumb or finger nail in opening the spout.

My invention further consists in the novel construction of parts and devices and in the novel combination of parts and devices herein shown and described and more particularly specified in the claims.

In the accompanying drawing forming a part of this specification, Figure 1 is a plan view of a paper or fibrous material can or

receptacle embodying my invention. Fig. 2 55 is a central, vertical section on line 2—2 of Fig. 1. Fig. 3 is a central, vertical section on line 3—3 of Fig. 2. Fig. 4 is a perspective view, showing the hinged spout swung open. Fig. 5 is a section similar to Fig. 2, 60 but showing a modification in which the tang at the free or swinging end of the spout is left projecting instead of being folded over the scored portion of the receptacle wall. Fig. 6 is a plan view of a modification, in which the tangs for securing the back of the sheet metal spout to the scored or opening portion of the cover wall or receptacle are located at the side edges of the back portion of the spout instead of at the 70 free end thereof.

In the drawing, 1 represents a paper can or receptacle, and by use of the term "paper" in the specification and claims, I mean any suitable fibrous material. The 75 paper receptacle has the customary body 2, bottom head 3 and cover 4, these parts being of any suitable or well known construction. 5 is an opening and closing sheet metal spout having a flat or back wall 6 and 80 two integral side wings 7, 7, preferably quadrant shaped. The spout is provided at one end of its back wall with a lip or tang 8 which is inserted through and clenched around the wall of the receptacle to which 85 the spout is attached, it being preferably attached to the flat or disk portion of the cover member 4 of the receptacle. The wall of the receptacle adjacent to the hinge tang or lip 8 is preferably provided with a fine score 9 90 on the inner side to facilitate the turning of the portion 10 of the receptacle wall, against which the back portion of the spout member fits, without breaking. The opening portion 10 of the receptacle wall against 95 which the back of the spout fits is bounded at its edges by scores 11, preferably formed upon the inside of the receptacle wall to adapt the same to readily sever when the spout is swung open, while at the same time 100 not interfering with the tight closure of the receptacle prior to the opening of the spout. A further score 12 preferably extends transversely at the free or swinging end of the spout at each side of the integral tang or 105 lip 13 with which the spout is preferably provided at its free end. This lip or integral extension 13 may be folded over the

end of the opening portion 10 of the receptacle wall, as illustrated in Figs. 1, 2 and 3 to secure the opening portion 10 to the back wall of the spout. Or if preferred, the opening portion 10 of the receptacle wall may be secured to the back wall of the spout by integral tangs 14 stamped out of the back wall of the spout and folded over the side edges of the opening portion 10 of the receptacle wall, as illustrated in Fig. 6, in which case the lip 13 at the free end of the spout may be left projecting to afford a better finger piece. If desired also, the lip 13 may be left projecting as indicated in Fig. 5 and the opening portion 10 of the receptacle wall left unsecured to the back wall 6 of the spout.

To limit the opening movement of the spout, its sides or wings 7, 7 are furnished with integral stop lips or projections 15, the same preferably extending in the plane of the wings, as shown in Figs. 1 to 5, although the same may be bent at an angle, if preferred, as shown in dotted lines in Fig. 6, where these stops are marked 16. The integral sides or wings 7, 7 of the hinged or opening and closing spout 5 are normally divergent from each other from the back wall of the spout toward the outer portion 17 of these wings so that as the spout is opened, the wings, which are of tin plate or other elastic spring metal, will be forced toward each other in the opening of the spout by the edges of the pouring opening formed by removing or forcing outward the opening portion 10 of the receptacle wall. The wings of the spout thus form a tight closure with the pouring opening in the receptacle wall when the spout is open. This action is facilitated also by having the hinge connection between the spout and the receptacle wall at the wider end of the back portion of the spout so that as the quadrant shaped wings swing through the pouring opening in the opening of the spout, the outer portion 17 of the wings will be forced together, the back portion 6 of the spout being preferably made tapering from its hinge end toward its free end as shown in Figs. 1 to 4. In my invention, however, the narrower end of the back portion of the spout may be the one which is hinged to the receptacle wall, as shown in Fig. 6. Although the paper or other wall of the can to which the back 6 of the sheet metal spout 5 is pivotally connected by its integral hinge tang 8, is itself ordinarily a sufficiently pliable and flexible fabric to afford, in connection with the score 9 a reasonably durable hinge connection between the spout and the receptacle wall adjacent the pouring opening, the hinge connection may be made more durable, if desired, by pasting or otherwise applying to the wall of the receptacle a reinforcing pliable fabric layer or member 18 of thin,

tough paper, cloth or other flexible material at the hinge end of the spout, and through which the hinge tang 8 extends, as shown in Fig. 6 of the drawing.

I claim:—

1. A paper receptacle having a wall thereof composed of a single thickness of material and provided with a spout-opening portion, and a sheet metal opening-and-closing pouring spout having a back member and two side members, said spout having at one end an integral tang securing it by a hinge connection to said wall, the back member of the spout normally lying flat against the inner side of the spout-opening portion of said wall, substantially as specified. 75

2. A paper receptacle having a wall thereof composed of a single thickness of material and provided with a spout-opening portion, and a sheet metal opening and closing pouring spout having a back member and two side members, said spout having at one end an integral tang securing it by a hinge connection to said wall, said spout-opening portion of the receptacle wall having scores at the edge thereof to facilitate its severance by the opening of the spout, substantially as specified. 85

3. A paper receptacle having a wall thereof composed of a single thickness of material and provided with a spout-opening portion and an opening and closing spout having a back member and two side members, said spout having at one end an integral tang securing it by a hinge connection to said wall, said spout-opening portion of the receptacle wall having scores at the edges thereof to facilitate its severance by the opening of the spout, said spout having furthermore an integral tang embracing the spout-opening portion of the receptacle wall, whereby the spout-opening portion of said wall remains fastened to the back member of the spout when the latter has been 105 opened, substantially as specified. 100

4. A paper receptacle having a wall thereof composed of a single thickness of material, and provided with a spout-opening portion, and a sheet metal opening and closing pouring spout having a back member and two side members, said spout having at one end an integral tang securing it by a hinge connection to the receptacle wall, said side wing members of the spout being normally divergent and adapted to be sprung toward each other as the spout is opened by engagement with the edges of the spout opening as the spout is swung open, and being furnished with stops at 125 their free ends to limit the opening movement of the spout, substantially as specified. 115

5. The combination of a receptacle having a slit in one of its walls, with a discharge spout on the interior of said receptacle and 130

having a nose projecting through said slit, and means securing said spout to the interior face of said wall of the receptacle.

6. The combination of a receptacle having 5 a slit in one of its walls, with a sheet-metal discharge spout having integral teeth extending through the wall of said receptacle from the interior side thereof and securing said spout on the interior face of said wall 10 adjacent said slit, and a nose on the spout extending through said slit to the exterior of the receptacle.

7. The combination of a receptacle, a discharge spout secured within said receptacle 15 to the interior face of one of the walls thereof, said receptacle having means on the ex-

terior of said wall indicating where said wall is to be cut to enable the spout to be turned outward into discharge position.

8. The combination of a receptacle, a discharge spout within said receptacle and secured to the interior face of one of the walls thereof, means on the exterior face of said wall indicating where the wall is to be cut to enable the spout to be turned to discharge 20 position, and an element exterior to the receptacle to facilitate turning the spout to discharge position. 25
